Primary Examiner — Steven J Czyz(74) *Attorney, Agent, or Firm* — Todd R. Miller(57) **CLAIM**

The ornamental design for an umbrella, as shown and described.

DESCRIPTION

FIG. 1 is a perspective view of an umbrella;

FIG. 2 is a front view thereof;

FIG. 3 is a right side view thereof;

FIG. 4 is a left side view thereof;

FIG. 5 is a top view thereof; and,

FIG. 6 is a bottom view thereof.

The broken lines depict portions of the article that form no part of the claimed design.
